UNITED STATES PATENT OFFICE.

JOHN W. FULPER, OF ANNANDALE, NEW JERSEY.

VACUUM-CLEANER.

1,077,518.

Specification of Letters Patent.

Patented Nov. 4, 1913.

Application filed July 17, 1911. Serial No. 639,002.

To all whom it may concern:

Be it known that I, JOHN W. FULPER, a citizen of the United States, residing at Annandale, in the county of Hunterdon, State of New Jersey, have invented certain new and useful Improvements in Vacuum-Cleaners; and I do hereby declare the following to be a full, clear, and exact description of the invention, such as will enable others skilled in the art to which it appertains to make and use the same.

This invention relates to new and useful improvements in vacuum cleaners.

An object of this invention is the provision of an apparatus which is so connected to a vacuum producing device that when the same is passed over a surface, the dust and other accumulations will be swept into the apparatus from whence it will be conveyed to a convenient receptacle.

A further object of this invention is to improve and simplify vacuum cleaning devices rendering them comparatively simple and inexpensive to manufacture, reliable and efficient in use and readily operated.

With the above and other objects in view this invention resides in the novel features of construction, formations, combinations and arrangements of parts to be hereinafter more particularly described, claimed and illustrated in the accompanying drawings, in which:

Figure 1 is a side elevation of my improved vacuum cleaner. Fig. 2 is a top plan view thereof. Fig. 3 is a front elevation thereof. Fig. 4 is a horizontal sectional view taken on the line 4-4 of Fig. 1. Fig. 5 is a longitudinal sectional view taken on the line 5-5 of Fig. 1. Fig. 6 is a vertical transverse sectional view taken on the line 6-6 of Fig. 3, and Fig. 7 is a view illustrating a modified form of shoe.

Referring to the accompanying drawings throughout the several views by similar characters of reference, the numeral 10 designates generally my improved vacuum cleaning apparatus which consists of a casing 11, the front and rear walls 12 of which are upwardly curved to the rearwardly slanting tubular extension 13 which is internally threaded as at 14 and reinforced for engagement with a tubular handle 15, to which a vacuum producing apparatus is attached,

while the opposite ends 16 of the said casing extend in parallel relation to each other adjacent the upper end of the said casing at which point they are curved inwardly as at 17 to meet the lower end of the said tubular extension 13.

The lower terminals of the ends 16 of the casing are offset as indicated by the numeral 18 and have formed integrally thereon spaced plates 19 which extend in parallel relation to the end walls 16, to the intermediate portion of which they are connected by sleeves 18' formed integrally upon the said plates 19 and end walls 16. The lower terminals of the plates 19 extend slightly below the offset terminals 18 of the walls 16, as indicated by the numeral 19' to produce shoulders 20 for the engagement with sliding shoes 21 which are removably secured to the lower ends of the said casing by countersunk screws or bolts 22 threaded through the offset extensions 18. These shoes 21 are used to slide over carpets or the like, but when it is desired to clean hardwood floors these shoes may be removed and replaced by felt lined supporting shoes 23 as indicated in Fig. 7. The plates 19 have extending through their central apertures 24 studs 25 which support keyed to their outer ends pinions 26. The opposite ends of these studs 25 are enlarged as at 27 for engagement with the sleeves 18, the said enlargements being provided with confronting sockets 28 for engagement with the outer terminals of a pair of shafts 29. These shafts 29 extend through a core 30 for engagement with the angular openings formed in the enlarged portions of the studs 25 and serve to hold the studs against displacement and also to cause the shafts to rotate upon the rotation of said studs. The core 30 is provided with a central passage or socket 31 into which extend the adjacent ends of the shafts 29. These shafts are provided with operating fingers 32 constituting a means whereby the said shafts may be moved inwardly against the tension of a spring 33 which surrounds the adjacent ends of the shafts and normally forces them into engagement with the studs. Vertically movable plates 34 are slidable upon the studs 25 and are provided with stud receiving slots 35 for the reception of the same to permit of their vertical move-

ment. These plates 34 are circular in formation and provided with concentrically disposed outwardly extending pins 36 which engage inwardly directed sleeves 37 formed upon the inner face of the supporting wheels 38. These supporting wheels 38 are provided with inwardly extending annular flanges 39, the said flanges being internally toothed, as indicated by the numeral 40 for engagement with a pinion 41 mounted upon a stub shaft 42 carried by the plate 19. This pinion 41 meshes with the before mentioned pinion 26 thereby imparting a rotary movement to the core 30 upon movement of the machine which causes the rotation of the wheels.

The flanges 39 are peripherally grooved as at 43 for engagement with rubber tires 44, thus serving to absorb noise caused by the passing of the machine over rough or uneven places. The core 30 is provided with a plurality of radially extending bristles 44' which are of sufficient length to engage the surface of the floor upon which the machine operates and thereby upon its rotation agitate the dust and dirt which is then removed through the tube 15.

In order to normally hold the wheels in their relative position with respect to the brush 45 formed by the core and bristles extending therefrom, the plates 34 are each provided with inwardly extending ears 46, each of which is provided with a threaded aperture 47 for receiving a screw 48. This screw 48 is provided at its outer end with thumb wings 49, while the inner terminal is reduced as at 50 to provide a shoulder to engage springs 51 extending between the said shoulder and the top of the casing 11, as indicated by the numeral 52. The screws provide a means whereby the tension of the said springs 51 can be regulated.

The plates 34 are further held against displacement by means of a connecting rod 53 which engages threaded apertures formed in the inner faces thereof and extend in the rear of the casing 11 in spaced parallel relation thereto. The opposite end walls 16 of the casing 11 are connected by arcuate plates 55. These plates are spaced from each other at their upper ends to produce passages 56 which communicate with the opening 57 formed at the juncture of the casing 11 and tubular extension 13. The lower terminals 55 of the said plates 55 are slotted to produce passages 58 through which and through the passages 56 the dirt or the like will be sucked by the vacuum producing apparatus connected with the tubular member 15.

The dust or other similar light substance will be drawn through the tube 15 into a suitable vacuum producing apparatus not shown in the drawings, while all heavy substance such as sand or the like will be swept through the openings 58 and permitted to

rest within the bottoms of the passages 59 located between the side walls 12 of the casing 11 and arcuate plates 55. The heavy matter may be removed therefrom upon the removal of the shoes 22 or 23.

From the foregoing disclosures taken in connection with the accompanying drawings, it will be manifest that a vacuum cleaning apparatus is provided which will fulfil all the necessary requirements of such a device.

Having thus fully described this invention what I claim as new and desire to protect by Letters Patent, is:

1. The combination in a vacuum cleaning device such as described, of a casing, shafts located therein, a brush removably secured within the casing by said shafts, plates formed upon the casing, plates slidably engaging these first mentioned plates, studs extending through the plates, wheels journaled upon the second mentioned plates and means operatively connecting the wheels with the shafts for rotating the brush, upon the rotation of the wheels.

2. The combination in a device such as described of a casing comprising opposite side and end walls converged at their upper ends and terminating in a tubular extension, arcuate plates connecting the end walls of the casing, a brush rotatably mounted between said arcuate plates and shoes removably secured to the plates and connecting the lower edges of the casing with the arcuate plates.

3. The combination in a device such as described, of a casing comprising opposite side and end walls, converged at their upper ends and terminating in a tubular extension, arcuate plates connecting the end walls of the casing, vertical plates integrally formed upon the outside of the end walls of the casing, and provided with sockets, studs located within said sockets and extending through the plates, outer plates slidably upon the first named plates, wheels journaled upon the outer plates and geared with the studs, shafts passing through the casing and connected to the studs, and a brush supported by the shafts.

4. The combination in a vacuum cleaning apparatus such as described of a casing comprising opposite side and end walls and provided with a tubular extension, arcuate plates connecting the end walls of the casing, said plates being spaced from each other and from the casing at their upper edges and formed with slots adjacent their lower edges, shoes secured to the lower side of the casing and connecting the same with the lower edges of the arcuate plates, plates secured to the end walls of the casing, sleeves connecting these said plates to the said end walls, shafts slidable through said sleeves, a brush carried by the said shafts, plates slidable upon the first mentioned plates, studs ex-

tending from these last mentioned plates, internally toothed wheels journaled upon said studs, gears meshing with said toothed wheels and operatively connected with the 5 brush and springs yieldingly holding the casing against movement relatively to the second mentioned plates.

In testimony whereof, I affix my signature, in presence of two witnesses.

JOHN W. FULPER.
